UNITED STATES PATENT OFFICE.

CHARLES KING, OF PORT HURON, MICHIGAN, ASSIGNOR OF SEVEN-TWELFTHS TO MARY E. KING, OF PORT HURON, MICHIGAN.

TABLE.

SPECIFICATION forming part of Letters Patent No. 784,945, dated March 14, 1905.

Application filed January 25, 1904. Serial No. 190,623.

To all whom it may concern:

Be it known that I, CHARLES KING, a citizen of the United States, residing at Port Huron, in the county of St. Clair and State of Michigan, have invented certain new and useful Improvements in Tables, of which the following is a specification.

My invention relates to improvements in extension-tables; and its object is to provide slide mechanism that will form a shield or cover by means of which the extended portion of the table will disclose a full-width closed rail. I attain this object by the mechanism illustrated in the accompanying drawings, in which—

15 Figure 1 is a transverse sectional elevation of the frame and top of the table on the line xx of Fig. 2. Fig. 2 is a longitudinal section of the same, and Fig. 3 is a longitudinal elevation of the leaves and extension slides and inclines with the cleats E removed to show the inclines.

Similar letters refer to similar parts throughout the several views.

A represents the top of the table.

25 C represents the extension-slides, and in applying these slides I form guideways F, attaching one to each end of the table-top A by means of screws through the flanges f' , screwed into the top A and the cross-cleats H 30 H', as shown in Fig. 1, forming receptacles f at the ends to act as guideways for the slides C to slide in.

I attach inclines D to the inner surface of the slides C and corresponding inclines D' to the lower surface of the leaves B, so that when the leaves are raised up and drawn back, as indicated by the dotted lines in Fig. 3, they will be supported exactly level with the top of the table.

40 The pins d in the slides C and the corresponding slots in the inclines D' are designed to hold and lock the leaves B to place when down and inclosed within the table, so that they cannot slide and rattle when the table is being moved.

The end rails G' are attached to the ends of the slides C, so that they will be drawn out or slid in with the slides in extending or contract-

ing the table, and the side rails G are secured to the guides F by screws or otherwise and 50 may be made plain or ornamental on the outer surface at the pleasure of the manufacturer.

I represents a portion of the center leg, and I' represents portions of the corner-legs of the table.

h h represent strengthening-bars in the slide mechanism of the table, and b b are dowels for interlocking the edges of the leaves.

This invention relates to tables that extend at the ends, the body of the table remaining 60 stationary.

The guides F are made of sheet-steel, light enough not to encumber the table, and are strengthened by the side rails G, as hereinbefore indicated.

65 The object of extending the side rails G well up into the top A is twofold: first, to avert the presence of a deep notch at the ends of the leaves when the table is extended, and, second, to extend the upper receptacles f' of the guides F well up above the lower surface of the laps, thus allowing the slides C to be made practically the full width of the rails G, and completely cover the leaf-receptacles, &c., when the table is extended.

75 Having thus fully described my invention, what I claim as new, and desire to secure by Letters Patent of the United States, is—

1. A table-frame, a table-top supported on said frame and having notches cut from the 80 lower surface at the edges, and cross-rails in the frame below the table-top, in combination with sheet-metal side rails secured to the under surface of the table-top bent up at the end of the lower surface of the top and extending to the surface of the projecting ends of the table-top, thence bent out and extending toward the ends of the top, thence bent down and extending below the top surface of the cross-rails, thence bent and extending 85 to the ends of the cross-rails, thence bent up and extending to the upper surface of the cross-rails and thence bent horizontally and secured to the tops of the cross-rails, forming slide-receptacles, each having three smooth 90 metallic bearing-surfaces above and below,

and slides fitted to coact with said receptacles, substantially as and for the purpose set forth.

2. In combination with a table-frame, a table-top having the ends cut away forming a 5 square receptacle on the under side, cross-rails in the frame; metal rails having each edge bent thrice at right angles forming a metallic guideway at each edge and a flange for securing the rails to the surface of the table-

top and of the cross-rails, and a slide fitted into the said guideways.

Signed at Grand Rapids, Michigan, January 7, 1904.

CHARLES KING.

In presence of—

I. J. CILLEY,
C. V. CILLEY.
